UNITED STATES PATENT OFFICE.

ALBERT HOSSFELD, OF LEWISTON, MINNESOTA.

BENDING MACHINE.

Application filed July 11, 1923. Serial No. 650,844.

To all whom it may concern:

Be it known that I, ALBERT HOSSFELD, a citizen of the United States, residing at Lewiston, in the county of Winona and 5 State of Minnesota, have invented certain new and useful Improvements in Bending Machines; and I do hereby declare the following to be a full, clear, and exact description of the invention, such as will enable 10 others skilled in the art to which it app pertains to make and use the same.

This invention relates to a bending machine of a simple type adapted to bend cold or hot material, the machine being of a type 15 adapted to be attached to a post or bench in a shop and being operable by hand. Such bending machines are of great utility in small blacksmith's shops, garages, farm shops, spring factories, etc.

20 It is an object of this invention to provide a simple and compact bending machine of minimum size and weight which will quickly and efficiently bend bars up to approximately one inch in diameter or of cross 25 section one-half inch by three inches, as well as tubing and piping.

It is a further object of the invention to 30 provide such a machine comprising a fixed frame and a bending frame swingingly connected thereto, said frames being adapted to carry various bending anvils and bending members, which members preferably are adjustably held in position.

It is more specifically an object of this 35 invention to provide such a machine having a main frame and bending frame, both comprising spaced horizontally disposed bars connected by a vertical pivot pin together with adjustable means on said frame 40 for accurately bending flat bars into curved, as well as sharp angular bends and to bend rods and flat stock into eye bars which bends are perfectly made.

It is more specifically an object of the 45 invention to provide such a machine as above described having a spacing block between the horizontal members of the main frame apertured to receive the stems projecting from various bending members, such 50 as an oscillatable spring bending anvil or a bending yoke for making square bends in flat stock, together with means for adjustably holding said stems in said spacing block.

55 It is also an object of the invention to provide means mounted at the top of the

main and bending frames, respectively, for making sharp angular bends in flat or round stock.

These and other objects and advantages 60 of the invention will be fully set forth in the following description made in connection with the accompanying drawings in which like reference characters refer to the same parts throughout the different views, 65 and in which,

Figure 1 is a plan view of the machine;

Fig. 2 is a view in front elevation of the machine;

Fig. 3 is a view in side elevation thereof, 70 as seen from the left of Fig. 1;

Fig. 4 is a horizontal section taken on the line 4—4 of Fig. 2;

Fig. 5 is also a plan view of the machine 75 with other parts in place therein;

Fig. 6 is a view in front elevation of the machine arranged as shown in Fig. 5 with the frames in oppositely extending position;

Fig. 7 is a horizontal section taken on the line 7—7 of Fig. 6; and 80

Fig. 8 is a partial plan view showing the machine equipped for bending pipe. In Figs. 4 and 8, a different position of the parts is shown in dotted lines.

Referring to the drawings, the machine 85 comprises a main or stationary frame comprising the spaced horizontal bars 1 bent at one end to be disposed somewhat adjacent each other and bolted together in spaced relation by headed and nutted bolts 90

2. The main frame is adapted to be connected to a post, work bench or other similar suitable member and, in the embodiment of the invention illustrated, the same is 95 shown as secured to a bench by being bolted to the brackets 3 which are, in turn, bolted to the bench 4. The bars of the main frame are each provided with a series of spaced vertically extending and aligned holes 5.

A spacing block 6 is held in position between the bars 1 somewhat adjacent the rear of the stationary frame, which block is held by a bolt or pin extending through a pair of holes in said bars and in the embodiment of the invention illustrated, said block is 100 held by a bolt which also forms a securing bolt attaching the frame to the bracket 3. The spacing block 6 has a lug 7 projecting laterally therefrom at its front side, the front surface of which is flat and extends 105 across said block and forms the front surface of a cylindrical boss 10 which extends 110

rearwardly at the other side of said block and is apertured to receive a stem 8 projecting from and secured to the adjacent ends of a closed yoke member 9. The stem 8 is equipped with a nut 11 threaded thereon and bearing against the boss on the rear of the block 6. The yoke 9 is formed with right angle bends at its front portion and is of material which is rectangular in 10 cross section.

A bending frame is provided comprising spaced horizontal bars 12 bent to lie somewhat closely adjacent at one end where they are spaced by a flattened hollow handle 13 and to which they are secured by spaced headed and nutted bolts 14. The bending frame is pivoted to the main frame by a pivot pin 15 extending through aligned vertical holes adjacent the ends of said 15 frames and said pivot pin has a portion of reduced diameter at its upper end and a portion of reduced diameter at its lower end below the lower bar 1 supported upon a swinging supporting member 16 carried by 20 a headed and nutted bolt 17 extending through one of the holes in the bar 1. As shown in Fig. 1, the upper and lower sides of the members 16 are not in alignment and the pivot pin 15 may be supported upon the 25 upper side or the lower side of said member. The bolt 17 also passes through one end of a flat member 18 extending rearwardly and provided with a U-bend through which passes a headed and nutted bolt 19, which 30 bolt also passes through one of the vertical holes in the lower bar 1. A circular gauge supporting member 20 preferably formed from a round rod has its ends bent around the bolt 19 and disposed, respectively, above the member 18 and in the U-shaped bend 35 therein. A rod 21 has its inner end bent around the bolt 17 and spaced from the member 16 by washers 22, and said rod carries a U-shaped gauge member 23, said member being adjustably held thereon by a set 40 screw 24 and having a vertically extending gauge pin 25 secured therein. Another gauge block 34 is also slidably mounted on the gauge supporting member 20 and held in 45 adjusted position thereon by a thumb screw. An anvil or presser block member 26 having one side of angular shape is mounted on the pivot pin 15 between the bars 12. Another anvil block 27 substantially square in 50 cross section has vertical holes extending eccentrically therethrough and is held between the bars 12 by a pin 28 extending through a hole therein and a pair of the aligned holes 12a in the bars 12. The pin 28 has a flattened head projecting through a slot formed longitudinally in a member 29 having a triangular pointed outer end and a threaded stem at its inner end, which stem passes 55 through the apertured upper end of a pin 30 extending through one of the holes in

the top bar 12 and having a reduced portion extending through the bottom hole therein, said pin being thus supported on the lower bar 12. The upper end of pin 30 is transversely apertured to receive a split 70 key bearing on member 29 and supporting said pin. A knurled nut 31 engages the threaded stem of member 29 and bears against the upper end of pin 30 so that the member 29 can be adjusted longitudinally 75 of the bending frame. A U-shaped bar 32 is disposed on top of the upper bar 1 of the main frame and clamped in position thereon by a headed and nutted bolt 33 extending through a pair of aligned holes in the bars 1. A rod 35 extends through the handle member 13, has a cross handle rod at its other end and is threaded at its inner end where it passes through a nut 36 abutting the inner end of handle 13. 80

The machine arranged as described is used for bending flat bars into sharp angle bends. In the operation, a piece of flat stock shown as *a* in Fig. 4 is inserted against the presser block 26 through the end of the yoke 9 and the bending frame is swung substantially at right angles to the main frame, as shown in Fig. 4, and the anvil block 27 brought squarely against the side of the stock *a*. The bending frame is now swung in a clockwise direction and the stock *a* is bent, as indicated by the dotted lines in Fig. 4, a sharp bend being formed therein about the inner corner of the yoke member 9. The presser block 26 and the anvil block 27 are in close proximity to the end of the yoke 9 and the sharp turn is thus made in stock *a* without any objectionable curling outwardly at the edges of the stock. If the bar of stock is not thus contacted closely adjacent the bend, this objectionable curling of the edges will occur and a perfect bend will not be formed. Furthermore, the close proximity of the anvil member 27 to the bending member 9 causes the side of the yoke to contact closely the sides of the member 9 so that a very sharp angle bend is produced. The block 26 is, of course, free to turn on its axis if necessary. At the start of the bending operation, however, one flat side of the block is in position against the side of the yoke 9. 90

A flat bend can also be made in a smaller piece of round or angular stock by means of the members 29 and 32. The bending frame is swung in a counter-clockwise direction to stand at substantially a right angle to the main frame and the piece of stock is placed across the end of the member 32 passing between the same and the upstanding portion of pivot pin 15 and is engaged on the side opposite the bar 32 by the member 29. The bending frame is then swung in a clockwise direction and the piece of stock will be given a sharp angle bend about the end of member 32 and is bent to position 95 100 105 110 115 120 125 130

lying along side of said member. The members 29 and 32 may be adjusted longitudinally of the main frame and bending frame so as to be brought to the desired position 5 to suit the stock. It will be also understood that the blocks 26 and 27 can be disposed in other positions on the main frame and bending frame by inserting their supporting pins through other pairs of holes provided. The 10 yoke 9 can be adjusted longitudinally of the main frame so as to be brought to the desired position by manipulation of the nut 11.

In the arrangement of the machine shown in Figs. 5, 6 and 7, the yoke 9 is removed 15 from the block 6 and an anvil member substituted therefor. This member comprises an eye bolt 40 having a threaded stem extending through the block 6 and equipped with an adjusting knurled nut 41. A headed and nutted bolt 42 passes through said eye bolt and arms 43 which have lugs disposed at each side of said bolt and clamped thereto by the bolt 42. The arms 43 diverge and have horizontal portions carrying inwardly directed pins which seat in apertures formed in lugs 44 disposed at each end of a semi-cylindrical block 45. The arms 43 also have pairs of lugs 46 projecting at each side of the bars 1 forming means 20 for guiding said arms longitudinally of the bars when the nut 41 is operated. A coiled tension spring 47 is secured to one side of a block 45 at one end and has its other end secured to the eye bolt 40. A bending member 48 formed of a flat plate is disposed between the bars 12 of the bending frame and is riveted to an offset bar 49, said bar and plate extending on opposite sides of a pin 28 which forms a guiding means 25 therefor. The inner end of the handle member 35 seats in a recess formed in the end of bar 49 and said bar is kept in contact with said end by a tension spring 50 secured to said bar and to one end of the handle 30 members 13. It will be understood, of course, that the blocks 26 and 27 are removed when the plate 48 and bar 49 are used. The machine, otherwise, is the same as already described in connection with 35 Figs. 1 and 4.

In the use of the machine arranged as shown in Figs. 5, 6 and 7, a flat piece of stock shown as *b* in Fig. 7, preferably adapted for use as a spring, such as used on automobiles and other vehicles, is operated upon. The bending frame is swung to the position substantially shown in Fig. 5. The stock is then inserted between the block 45 and the pivot pin 15, the same being engaged on the side engaged by the block 45 by the edge of the bending plate 48. The bending frame is then swung in a clockwise direction and the end of the piece of stock *b* is bent closely about the pivot pin 15. 60 When the bending operation is begun the

block 45 is in the position shown in Fig. 5 with its flat side extending parallel to the center line of bars 1. As the stock is bent around, the same contacts strongly against the block 45 and the latter is rotated with 70 the stock as the stock is pulled around the pin 15. The block 45 thus moves with the stock and the spring 47 is extended. If, however, the bending frame be moved backward a trifle so as to temporarily release 75 the stock the spring 47 will again pull the anvil to the position shown in Figs. 5 and 7. It will be noted that the surface of block 45 lies very close to the pin 15 and the piece of stock is contacted throughout its width 80 by the edge of the plate 48. The end of the stock is thus bent about the pin 15 and the eye formed therein without any chance for the stock to curl outwardly at the edges as it will do if it is not contacted firmly adjacent the bent portion. The block 45 can be adjusted to suit the stock by manipulation 85 of nut 41. The bending plate 48 can also be moved toward the pivot of the frames by advancing the jaw rod 35. When said 90 jaw rods retract the spring 50 will pull the plate 48 and bar 49 outwardly.

In Fig. 8, both the yoke 9 and the spring bending block 45 are removed with their 95 attached parts and a block 51 is used. This block is somewhat elongated with curved sides having formed therein semi-circular grooves. The block is held in position, as shown, between the bars 1 by a pin extending through a pair of the holes in said bars. A bending roller 52 is carried between the bars 12 on a pin extending through a pair of holes therein. The block 51 is adapted for the bending of pipe or tubing and in the operation thereof, a piece of pipe *c* will be placed against the flat side of the spacing block 6 extending between the same and one side of block 51. The bending frame is now swung to the position indicated in dotted lines in Fig. 8 and the roller 52 brought against one side of the pipe. The bending frame now being swung clockwise, the pipe will be bent, as shown in full lines in said figure. By moving the pipe slightly between the bending operations, the same can be bent into a complete circle or in a plurality of coils. 105

Where several pieces are to be bent in the machine to the same angle, the gauge members 23 and 34 may be used. The member 23 can be used to locate the end of the piece of stock to be bent and the member 34 can be set to proper place on the supporting member 20 to indicate the angle to which the stock is to be bent. The thumb screws 110 used to position the members 23 and 24 can be easily operated and said members quickly adjusted.

From the above description it is seen that 115 the applicant has provided a simple, compact

and very efficient bending machine and one which will have a very high degree of utility in small shops, garages and other places where a comparatively small stock is to be bent to form such members as eye bolts, clevises, links, circles, angles, offsets, braces, cranks, etc. The machine will also bend standard pipe and tubing smoothly and perfectly without flattening or kinking. The 5 spring bending attachment comprising the block 45 can be used and the machine will then bend or roll perfect eyes for automobile and other springs. The machine is made as light as consistent with the requisite strength and the various adjustments of the parts can be quickly and easily made. The machine is, as stated, very simple, and is capable of handling a large number and variety of work. The machine is easily 10 transportable, very durable and is made and sold at a very reasonable price. The machine has met with great favor commercially and its success and efficiency, in actual practice, have been thoroughly demonstrated.

It will, of course, be understood that various changes may be made in the form, details, arrangement and proportions of the parts without departing from the scope of 15 applicant's invention, which, generally stated, consists in a device capable of carrying out the objects above stated, and such as shown and described and set forth in the appended claims.

35 What is claimed is:

1. A bending machine comprising a stationary frame having spaced horizontal bars, a spacing block therebetween and transversely apertured to receive successively a plurality of different members adapted 40 to be contacted by the work, a bending frame pivoted to said main frame, and a bending member carried by said bending frame for contact with the work.

45 2. A bending machine having in combination, a stationary frame comprising spaced substantially parallel members, a bending frame comprising spaced parallel members, a pivot connecting said frames adjacent the ends thereof, a block disposed on said pivot having two faces meeting at an angle to form an edge, said faces being joined by a curved surface, a work contacting member carried by said stationary frame, a bending member carried by said bending frame adapted to bend a piece of work engaged by said block and by said work-engaging member.

50 3. A bending machine comprising a stationary frame, comprising spaced parallel members, a pivot member extending through and between said members, a block mounted on said pivot member having a transverse aperture therethrough at one side of said pivot member, a member adapted to be

contacted by the work carrying a threaded stem, said stem passing through said aperture, means for adjusting said last mentioned member longitudinally of said stationary frame, and a bending frame member 55 pivoted to said stationary frame.

4. A bending machine comprising a stationary frame, a block therein having a transverse aperture therethrough, a rectangular shaped yoke of rectangular cross section disposed in said stationary frame having, its ends projecting beyond the same, an anvil block in said stationary frame closely adjacent said yoke, a bending frame pivoted to said stationary frame, and a bending anvil of rectangular cross section carried in said bending frame adapted to contact with its flat side a bar of stock extending through said yoke and against said anvil block.

5. The structure set forth in claim 4, said yoke being mounted for movement longitudinally of said stationary frame, and means for moving said yoke and holding the same in various positions.

6. The structure set forth in claim 4, a member rotatably mounted in said main frame about a vertical axis, said yoke having a stem extending through said member, and means on said stem for moving and holding said yoke in various positions.

7. A bending machine comprising a main frame, a bending frame, a member mounted at the top of said main frame having a flat side surface and a sharp corner at one end, a member mounted at the top of said bending frame and having a sharp bending edge for bending a piece of work about said first mentioned member, a pivot member connecting said frames and projecting between said members to form a work anvil about which a piece of work held by said first mentioned member may be bent by said second mentioned member.

8. The structure set forth in claim 7, said members on the top of said main frame and bending frame being movable longitudinally, respectively, on said frames, and means for holding said members in a plurality of positions thereon.

9. A bending machine comprising a stationary frame having vertically spaced horizontal bars, a bending frame equipped with a handle and also formed of vertically spaced horizontal bars, a pivot pin connecting said frames and extending above the same adapted to have work bent thereabout and a member disposed beneath said frames having spaced upper and lower arms for supporting said pivot pin.

10. A bending machine comprising a stationary frame having vertically spaced horizontal bars, a bending frame having vertically spaced horizontal bars, a pivot pin connecting the ends of the bars of said frames,

a block carried between said bars on said pivot pin and having angular surfaces at one side, a yoke member extending longitudinally between the bars of said stationary frame and contacting one of the surfaces of said block, and a block rectangular in cross section eccentrically mounted between the bars of said bending frame and adapted to co-operate with said block and yoke in the bending of the work.

11. A bending machine having in combination, a stationary frame, a bending frame, a pivot connecting said frames, a block having a longitudinal bore therethrough through which said pivot extends, said block having two substantially plane surfaces intersecting at an angle to form a longitudinal edge, said surfaces being joined by a substantially cylindrical surface.

12. A bending machine having in combination, a stationary frame, a bending frame including spaced members, a pivot member connecting said frames at their ends about which work is adapted to be bent, a block carried by said stationary frame and disposed between said spaced members thereof, a work engaging member carried by said stationary frame, means engaging said block as a base of re-action for adjusting said work engaging member longitudinally of said stationary frame, and an adjustable work bending member carried by said bending frame.

13. A bending machine having in combination, a stationary frame, a bending frame, a transverse pivot member connecting said frames adjacent their ends, a substantially rectangular yoke member disposed in a plane substantially parallel to the axis of said pivot member, means for adjusting said yoke longitudinally of said stationary frame, and a bending member adjustable

longitudinally of said bending frame for engaging and bending work held in said yoke.

14. The structure set forth in claim 13, said yoke having top and bottom sides and an end portion of angular cross section connecting the said sides, said bending member having a work-engaging portion parallel with the edges of said end portion of said yoke.

15. A bending machine having in combination a stationary frame comprising spaced substantially parallel members, a bending frame comprising spaced parallel members, a pivot connecting said frames adjacent the ends thereof, a block carried by said stationary frame, a work engaging member carried by said stationary frame and movable longitudinally thereof including means extending through said block, a member engaging said means and block adapted to adjust said work engaging member longitudinally of said frame, and a work bending member carried by said bending frame and extending between said parallel members thereof.

16. A bending machine having in combination, a stationary frame, a bending frame, a pivot member connecting said frames at their ends about the axis of which work is adapted to be bent, a work engaging member carried by said stationary frame, said member comprising two surfaces intersecting to form an edge, said member including a curved surface with which the work contacts, means for moving said work engaging member longitudinally of said stationary frame, and a bending member in said bending frame for engaging the work and bending the same.

In testimony whereof I affix my signature.
ALBERT HOSSFELD.
